TOBACCO PIPE

Horace Young Nutt, Radlett, England

Application October 9, 1933, Serial No. 692,858
In Great Britain February 7, 1933

8 Claims. (Cl. 131—12)

This invention relates to tobacco pipes and has for its object to provide a pipe with an improved form of cover for partially protecting the contents of the bowl from wind and moisture when in use without spoiling the appearance of the pipe.

According to the invention the cover for the bowl of the tobacco pipe or the like consists of a cover portion carried by a leg which extends down the outside of the pipe bowl and is pivoted

thereto at a suitable point. The side of the bowl over which the leg extends has a flattened portion, the leg having a flat inner face adapted to fit over this flattened portion and preferably a curved or rounded outer face which completes the usual contour of the bowl when the cover is in the closed position over the rim of the bowl.

The whole cover and the leg are preferably of wood, similar to that of the bowl and the cover part may be perforated and further an annular

gap may be provided between the rim of the bowl and the cover to insure that the necessary amount of air can be drawn into the pipe easily.

The cover is so mounted that it can be swung clear of the bowl and preferably down on to the stem of the pipe or over the front of the bowl. For this purpose the pivot point of the leg may be placed eccentrically to the vertical axis of the bowl and further a stop may be provided on the cover or on the rim of the bowl to prevent the cover being swung over the bowl in the opposite direction. The cover may be formed with a depending rim or with a dished interior or with both.

Further the cover may be carried by a pair of legs and may be arranged to swing over the side of the bowl and not over on to the pipe stem all as hereinafter fully described.

To enable the invention to be fully understood it will now be described by reference to the accompanying drawing in which:

Fig. 1 is a side elevation of a tobacco pipe having a cover according to one form of the invention applied thereto.

Fig. 2 is a plan view thereof and

Fig. 3 is a view of the back of the pipe bowl.

Fig. 4 is a back view of a pipe bowl showing a modified form of cover, and

Figs. 5 and 6 are side elevations of portions of tobacco pipes showing further forms of covers.

Referring first to Figs. 1—3. An ordinary briar tobacco pipe 6 is shown, fitted with a cover 7 having a leg portion 8 which extends down over one side of the bowl 9 and is pivoted thereto by a pin 10. As best seen in Fig. 3, the side of the bowl

55 is flattened at 11 and the leg 8 has a flat inner

face which covers the flattened portion 11 when the cover is in the closed position.

The outer face of the leg 8 is preferably curved or rounded to complete the usual contour of the bowl when the cover is in the closed position. The cover 7 is perforated at 12 and has a depending flange 13a so formed that when the cover is closed an annular air gap 13 is formed between the flange and the rim of the pipe bowl.

In Fig. 1 the full lines show the cover in the closed position and to uncover the bowl the cover is swung down on to the pipe stem or in front of the bowl into the position shown in dotted lines.

To enable the cover to clear the edges of the bowl when swung down the pivot pin 10 is eccentric to the vertical axis of the bowl. It will be seen from Fig. 3 that the pin does not extend completely through the wall of the bowl.

To prevent the cover from being swung over the back of the pipe a stop 14 is provided on the rim of the bowl. This stop may also be provided on the cover if desired or omitted if it is not desired to limit the swinging movement of the cover. The stop may be in the form of a detachable member such as a metal or other pin, plug or the like. Thus if the stop is removed the cover can be swung over the back of the pipe to facilitate access for cleaning.

The cover and the leg are preferably of wood to match the bowl and the cover and leg may be formed integrally, but this is not essential.

Various modifications of the invention are possible.

In the form shown in Fig. 4 a cover similar to that shown in Fig. 1 is provided with two legs 8 which extend over flattened portions on opposite sides of the bowl and are pivoted thereto by pins 10. Both legs are similar to the leg shown in Fig. 1.

Fig. 5 shows a two leg cover as in Fig. 4 but arranged to swing laterally over the bowl instead of down on to the pipe stem. A stop 14 may be provided to limit the swinging of the cover to one side only of the bowl or a detachable stop may be provided as hereinbefore described.

Fig. 6 shows a pipe bowl fitted with a cover 7 which is shaped to facilitate the cleaning of the interior of the cover. In this case the flange 13a extends only around the front of the cover the rim of the pipe bowl being sloped down from the back as shown at 15. The cover is shown in the closed position in dotted lines.

If desired cool air may be admitted to the

- pipe bowl through vents arranged adjacent to the bottom of the bowl. Preferably these vents are so arranged that they are covered by the leg or legs of the cover and the leg or legs may have grooves or holes formed therein adapted to communicate with the vents as will be understood. 80
- The examples illustrated show pivoted covers but a hinged arrangement is possible. 85
- 10 While the covers hereinbefore described are primarily intended for tobacco pipes they may also be used with cigarette holders of the "pipe" type. For instance, the bowl of the holder may be made sufficiently long to contain a cigarette 15 of normal length or even of a shorter length than usual, the bowl then being fitted with one of the covers according to the invention. A cigar holder could also be made on similar lines. In this description and in the appended claims 20 the words "tobacco pipe or the like" are intended to cover the application of the invention to cigarette and cigar holders.
- If desired the whole cover, or the disc part only, may be made of metal or other suitable 25 material. Or the disc may be of wood and the legs or side portions of metal or other suitable material.
- I claim:
1. A smoker's pipe comprising a bowl having an exterior surface portion with a flat lateral face, a cover for the bowl adapted to be closed over the open end of the bowl and having a leg with a flat inner face adapted to engage the flat lateral face of the bowl and having an exterior 30 face of a configuration to provide an extension of the exterior surface portion of the bowl, and a pivot securing the lower end of the leg against the side of the bowl to admit swinging of the cover into and out of closed position. 35
2. A smoker's pipe comprising a bowl having an exterior surface portion with opposed flat lateral faces, a cover for closing the open end of the bowl and having a pair of legs with inner flat faces engaging the flat lateral faces of the bowl, and pivots connecting the lower ends of the legs to the bowl, the exterior faces of the legs having configurations forming extensions and providing for the continuity of the exterior surface portion of the bowl. 40
3. A smoker's pipe comprising a bowl having flat exterior faces, a cover for the bowl having legs with flat inner faces engaging the flat exterior faces of the bowl and having outer faces curved as extensions and continuations of the exterior surface of the bowl, and pivots connecting the lower ends of the legs to the bowl and disposed coaxially at one side of the axis of the bowl to admit free swinging of the cover into and out of position over the bowl from one side 45 of the bowl and limit the swinging of the cover beyond its covering position. 50

- 135
- 140
- 145
- 150
4. A smoker's pipe comprising a bowl having exterior flat faces in its opposite sides, a cover having a pair of legs with inner flat faces engaging the flat faces of the bowl and having exterior rounded faces constituting extensions of the exterior surface of the bowl, and pivots securing the lower ends of the legs to the bowl, said legs being of a length to space the lower portion of the cover from the upper edge of the bowl when the cover is closed and provide a draft passage beneath the cover and insure even burning of tobacco in the pipe bowl. 80
5. A smoker's pipe comprising a bowl, a cover for the bowl, means for removably supporting the cover in closed position over the open end of the bowl, said cover having a marginal depending flange providing a dished underside for the cover and said supporting means being relatively located on the bowl to support said flange in spaced relation to the upper end of the bowl to admit air for combustion when the cover is closed. 85
6. A smoker's pipe comprising a bowl open at its upper end, a cover for the open end of the bowl, having depending arms disposed at the opposite sides of the bowl, pivots connecting the arms to the bowl for guiding the cover when swung into open and closed positions, and a stop carried upon the upper edge of the bowl adapted to engage the cover to limit the swinging thereof into closed position, said stop spacing the lower portion of the cover from the upper edge of the bowl to provide a draft opening between the bowl and cover when the latter is closed. 90
7. A smoker's pipe comprising a bowl open at its top and having a projection on its upper edge on one side of the bowl, a cover having an arm, and means for pivotally connecting the arm to the side of the bowl for holding the cover thereto for swinging into and out of position over the open end of the bowl, said projection adapted to engage said cover and hold the same from swinging over said side of the bowl and providing spacing means forming a slot between the cover and bowl when the cover is closed. 95
8. A smoker's pipe comprising a bowl open at its upper end and having at its upper edge and at one side a stop, and a cover having a pair of arms disposed at the opposite sides of the bowl and pivotally connected thereto for holding the cover in position to be swung into and out of closed position over the open end of the bowl, said cover adapted to engage said stop when in closed position to limit the swinging of the cover beyond the stop, the pivotal connection of said arms with the bowl being disposed to one side of the axis of the bowl remote from the projection whereby the cover may swing freely over the opposite side of the bowl. 100
